UNITED STATES PATENT OFFICE.

FREDRIK LJUNGSTRÖM, OF BREVIK, LIDINGÖN, SWEDEN, ASSIGNOR TO AKTIE-BOLAGET LJUNGSTRÖMS ANGTURBIN, OF STOCKHOLM, SWEDEN, A CORPORATION.

COOLING ELEMENT.

1,401,482.

Specification of Letters Patent. Patented Dec. 27, 1921.

Application filed January 28, 1920. Serial No. 354,759.

To all whom it may concern:

Be it known that I, FREDRIK LJUNGSTRÖM, chief engineer, subject of the King of Sweden, residing at Brevik, Lidingön, Sweden, have invented certain new and useful Improvements in Cooling Elements, (for which I have filed application in Sweden Jan. 21, 1919, D. N. O 241/19,) of which the following is a specification.

10 The present invention relates to an arrangement in cooling elements disposed beside each other, and the invention has for its purpose to provide for as large a cooling surface as possible within a limited space.

15 The invention consists in the elements being formed of flattened pipes provided on the outside with projecting ribs. The invention also consists in the fact that the ribs of the opposite faces of two adjacent cooling 20 elements are disposed so as to cross each other, the ribs on the opposite sides of each element being also arranged to cross each other, if desired.

25 In the accompanying drawing, an embodiment of the invention is shown by way of example. Figure 1 is a partial sectional elevation of an arrangement according to the present invention, and Fig. 2 is a cross section on line A—B of Fig. 1. Fig. 3 is an 30 enlarged sectional view, taken on lines C—D of Fig. 1, of part of an element according to the invention.

35 In Figs. 1 and 2, 1 denotes the elements which are inserted groupwise into the square pipe or chamber 2. The elements are provided with projecting ribs 3 so as to produce a larger cooling surface. Fig. 3 shows an

element drawn to a larger scale, both sides of the flattened pipe being provided with dents 4 touching each other on the inside so as to prevent the sides from being squeezed together, should there be a vacuum in the element.

An element with these projecting ribs or cams is extremely efficient, particularly when steam or water within the elements is being cooled by means of air circulating around the elements. Besides producing a larger cooling surface, the ribs bring about a whirling round of the air so that each particle of air is brought in contact with the element.

Obviously, the invention may be equally well applied to heating elements.

What I claim as new and desire to secure by Letters Patent of the United States is:—

1. A plurality of cooling elements arranged side by side and each consisting of a flattened pipe, and flat laterally projecting solid ribs provided on the outside of the pipe, extending obliquely from one edge to the other edge of the pipe and the ribs of the opposite walls of two adjacent cooling elements being arranged so that they cross each other.

2. An arrangement as set forth in claim 1 wherein the ribs on the opposed side of each cooling element cross each other.

In testimony whereof I affix my signature in presence of two witnesses.

FREDRIK LJUNGSTRÖM.

Witnesses:

P. H. BERGROPH,
OSCAR GRALEN.
